DESIGN FOR A SHOWER BRUSH

Ivan H. Yoshikawa, Manzanar, Calif.

Application September 1, 1943, Serial No. 111,039

Term of patent 7 years

To all whom it may concern:

Be it known that I, Ivan H. Yoshikawa, a citizen of the United States, residing at Manzanar, in the county of Inyo and State of California, have invented a new, original, and ornamental Design for a Shower Brush, of which the following is a specification, reference being had to the accompanying drawing, forming part thereof.

I claim:

The ornamental design for a shower brush, as shown and described.

IVAN H. YOSHIKAWA.
